UNITED STATES PATENT OFFICE.

WILLIAM E. MCCORMICK, OF CHICAGO, ILLINOIS, ASSIGNOR TO INTERNATIONAL TELEPHONE MANUFACTURING COMPANY, OF CHICAGO, ILLINOIS, A CORPORATION OF ILLINOIS.

MULTIPLE SWITCHBOARD.

SPECIFICATION forming part of Letters Patent No. 716,460, dated December 23, 1902.

Application filed August 26, 1901. Serial No. 73,361. (No model.)

To all whom it may concern:

Be it known that I, WILLIAM E. MCCORMICK, a citizen of the United States, residing at Chicago, in the county of Cook and State 5 of Illinois, have invented certain new and useful Improvements in Multiple Switchboards, of which the following is a full, clear, and exact description, reference being had to the accompanying drawings, forming a part of 10 this specification.

My invention relates to multiple switchboards, and particularly to the construction of spring-jacks or terminal sockets of telephone-lines in switchboards of this type; and 15 the object of the invention is to produce a strong and simple jack and a strip or range of jacks comprising a simple and economical organization of the parts.

The invention comprises certain organizations and arrangements of parts, which will be described in the specification and pointed out in the claims.

In the accompanying drawings, which illustrate my invention, Figure 1 is a broken top 25 view of a range or strip of spring-jacks embodying my invention. Fig. 2 is a plan view of the same strip from below. Fig. 3 is a rear elevation of the strip or range of jacks. Fig. 4 is a front elevation of the range or strip of 30 jacks, and Fig. 5 is a section taken vertically on the center line of an individual spring-jack.

The front rail of the frame of each range of jacks consists of two strips *a* and *a'* of suitable 35 insulating material and an interposed strip *b* of metal, the latter being provided with means at each end for attaching the same to the framework of the switchboard. The strip *b* is preferably bent near its ends, as shown in 40 Figs. 1 and 2 of the drawings, and is provided at its extremities with half-round grooves or sockets to receive a suitable attaching device, whereby the same is secured in place on the switchboard. The several 45 strips comprising the front rail of the frame of the range of jacks are suitably bored, as shown in Fig. 5, the bore of the metallic strip *b* being somewhat larger than the bores of the adjacent insulating-strips *a* and *a'*, whereby

the thimbles or test-rings *c* by which these several parts are united are out of contact with and properly insulated from the body of the metallic strip, as clearly shown in Fig. 5. The thimbles or test-rings *c* of the jacks are preferably somewhat flared at their front or exposed ends to present broad and rounded surfaces for the application of the testing-plug and to more readily center the line-plugs and to aid in binding the several strips of the rail together. The thimbles extend through 50 the front rail and are screw-threaded at their rear ends to receive the upturned ears *d* of associated terminal strips *d'*, the ears being correspondingly screw-threaded to engage the threads of the thimbles, whereby the terminal strips are electrically connected to their corresponding test-rings, as shown in 55 the drawings. The ears engaging the thimbles and the flared ends of the thimbles bind the several strips comprising the front rail 60 of the frame of the range or strip of jacks securely together, whereby these several parts are assembled together in a compact, strong, 65 and simple construction.

The rear rail *e* of the frame is a strip or 70 elongated block of suitable insulating material provided with transverse channels or grooves *e'* and *e''* on its upper and lower faces, respectively, having intermediate ribs *e³* and *e⁴*. 75

The terminal strips *d'* are secured near their rear ends in the grooves *e''* by suitable screws, as shown in Figs. 2 and 5, and their ends are formed with suitable means to secure electrical connection with the sides of 80 their respective lines. The terminals *d'* are preferably reduced in width toward their rear ends, where they enter the grooves of the block *e*, whereby uniformity of parts is secured in assembling the several elements. 85 The terminals *d'* lie throughout their lengths in a horizontal plane, whereby rigidity of the range or strip of jacks is obtained.

The spring *l* of each jack lies substantially 90 parallel with its associated terminal strip and 95 upon the opposite side of the center line of the jack, being provided at its front end near the rear end of the thimble with the usual

downturned angular contact portion to engage the plug. The springs are secured to the block *e* in the transverse channels or grooves *e'* of its upper face and toward their 5 rear ends beyond the line of the block are provided with lateral ears or lugs *l'* and *l*, which respectively engage the front and rear edges of the block and prevent longitudinal displacement, as well as insuring uniformity 10 of position in assembling the parts. The rear ends of the springs have suitable terminals. The springs are held in their channels by a suitable binding-strip *e⁵*, which is secured to the block by screws passing outside 15 and intermediate the springs, as shown in Fig. 1, an intermediate insulating-strip *e⁶* being used.

When the parts are assembled, the structure comprises a range or strip of jacks of 20 simple construction and compact organization which may be readily placed in and removed from the board. The strips *a* and *a'* of the front rail and the ribs *e⁴* of the rear rail project below the terminals *d'*, as shown in 25 Figs. 3 and 5, whereby when the strips or ranges of jacks are assembled in place one above another in the switchboard proper insulation of the ranges will be provided.

Having described my invention, I claim—
30 1. A range or strip of switches consisting of a front rail composed of outer and inner insulating-strips and an intermediate fastening-strip, all suitably bored, test-rings in the bores having flaring mouths and rear screw-threads, a channeled rear rail, terminal strips 35 in the channels of the rail and having tapped ears to engage the threads of the test-rings, spring-terminals secured to the rear rail and extending parallel with and above the strips.

2. A range or strip of switches consisting 40 of a front and rear rail, the latter having upper and lower channels, and the former consisting of insulating-strips and an intermediate fastening-strip provided with suitable bores, flared metallic sockets in the bores, 45 terminal strips having screw connections with the sockets and secured in the lower channels of the rear rail, springs in the upper channels of the rear rail having lateral ears, and a retaining-strip for the springs. 50

3. A range or bank of switches consisting of front and rear rails, the front rail being composed of outer and inner insulating-strips, and an intermediate fastening-strip, terminal strips connecting the rails, and spring-terminals on the rear rail, the rails extending below the plane of the strips to insulate the adjacent ranges or banks. 55

4. A range or bank of switches, consisting of a front rail composed of outer and inner insulating-strips and an intermediate fastening-strip suitably bored, metallic sockets in the bores having flaring front ends and screw-threaded rear ends, a rear rail having upper and lower channels formed by intermediate 65 ribs, terminal strips in the lower channels having threaded connections with the sockets, spring-terminals in the upper channels, a retaining-strip therefor, the front strips and ribs extending below the terminal strips 70 to insulate adjacent ranges.

In testimony whereof I affix my signature in the presence of two witnesses.

W. E. MCCORMICK.
